UNITED STATES PATENT OFFICE

129,930

DESIGN FOR A GAME BOARD

Robert Anton Sauer, Butte Meadows, Calif.

Application June 19, 1941, Serial No. 101,572

Term of patent 3½ years

To all whom it may concern:

Be it known that I, Robert Anton Sauer, a citizen of the United States, residing at Butte Meadows, in the county of Butte and State of California, have invented a new, original, and ornamental Design for a Game Board, of which the following is a specification, reference being had to the accompanying drawing, forming part thereof.

I claim:

The ornamental design for a game board, as shown.

ROBERT ANTON SAUER.
